UNITED STATES PATENT OFFICE.

HENRY CHARLES BRAUN, OF LONDON, ENGLAND, ASSIGNOR TO THE ANGLO-AMERICAN
PATENT BOTTLE COMPANY, LIMITED, OF LONDON, ENGLAND.

APPARATUS FOR REMOVING METAL CAPSULES FROM BOTTLES.

1,175,697.

Specification of Letters Patent. Patented Mar. 14, 1916.

Application filed September 3, 1913. Serial No. 787,985.

To all whom it may concern:

Be it known that I, HENRY CHARLES BRAUN, a subject of the King of England, residing at 236 Pentonville road, King's Cross, London, England, have invented certain new and useful Improvements in Apparatus for Removing Metal Capsules from Bottles; and I do hereby declare the following to be a full, clear, and exact description 10 of the invention, such as will enable others skilled in the art to which it appertains to make and use the same.

It is found in practice that considerable difficulty is experienced in removing hard 15 metal capsules or sleeves such as the aluminium capsules used for retaining non-refillable stoppers and the like devices, for preventing or rendering difficult the fraudulent refilling of bottles, upon the necks of such 20 bottles.

My present invention consists of a simple and efficient apparatus by means of which the capsules or sleeves may be easily and quickly removed from the bottle without 25 damaging the bottle itself or breaking the stopper portion attached to the top of the neck of the bottle by means of said capsule or sleeve.

In the general way of carrying out my invention I provide a suitable device for holding or keeping the bottle in the required position, means for preventing the sleeve or capsule from rotating upon or in respect to the neck of the bottle and a knife or knives 35 or other cutting tools adapted to be brought upon the said sleeve or capsule and to cut or tear and remove or partially remove such sleeve or capsule from the neck of the bottle; the means for preventing the sleeve or 40 capsule rotating in or with respect to the neck of the bottle may be a rubber pad, one or more fixed or spring controlled knives or the like or the rotation may be prevented by causing pairs of knives to operate in opposed directions upon the sleeve or capsule.

Additional means may be provided for completing the removal of the capsule after the preliminary stripping has been effected. Means may also be added for adjusting the 50 bottles or the like of different sizes in position for stripping in order that the apparatus may be accommodated for bottles of different sizes.

In one particular method of carrying out

my invention as applied to an apparatus 55 more especially intended for removing hard metal, such as aluminium capsules, upon a suitable base plate or foundation I mount a rest of suitable size and form for the reception of a bottle lying upon its side. This 60 rest which may be of metal or wood is also furnished with a ledge for steadyng the bottle when in position. A suitable rest is also mounted in connection with the base plate for the reception of the neck of the 65 bottle having an adjustable device controlled by a screw or the like the position of which may be altered so as to accommodate the apparatus for use with bottles of different 70 lengths and size. The rest or any of the 75 parts may be covered with leather, vulcanized fiber or other suitable material for diminishing the liability of breakage. Attached to the base plate is a suitable standard which carries a bearing coming above 80 the rest for the neck of the bottle. Through this bearing works a rod carrying at its lower end a block upon two sides of which are pivotally mounted cutting knives of particular formation. These knives are preferably formed of a number of laminæ having at their lower ends wedge or chisel like cutting edges, and comb springs preferably 85 are provided in connection with the block for normally pressing the knives toward one 90 another, suitable stops being furnished for keeping them in a substantially parallel position with respect to one another. The upper end of the rod carrying the block and the knives is pivoted to a long handle which 95 is again connected directly or by means of a link to the upper portion of the framework. The lever forming the handle is also extended beyond the link or pivot for some distance and connected by means of a tension spring to some suitable portion of the framework.

Mounted upon or in connection with the framework near the adjustable device coming against the neck of the bottle is a projecting pin or the like which may be made adjustable for facilitating the stripping as hereinafter explained. A pedal attachment may be used for lowering the handle and knives by means of the foot. And in order 105 that my said invention may be better understood I will now proceed to describe the same with reference to the drawings accom-

panying this specification in which is shown one method of constructing an apparatus according to my invention, more particularly suitable for removing hard metal capsules.

5 Figure 1 is a front elevation of the machine; Fig. 2 is a plan on the line A, B, Fig. 1; Fig. 3 is a detail hereinafter referred to. Figs. 4 to 8 show modified forms of the apparatus.

10 The same letters of reference are employed to denote the same parts in all the views.

15 *a* is a base or foundation plate of metal which has formed in one therewith a standard *b* provided with a vertical bearing *c*. *d* is another forked portion forming a bearing for a pivot pin *e* upon which a long arm *f* is mounted. This arm *f* is furnished at one end with a handle *g* and with a slot *h* 20 through which a pin *k* mounted in a fork *m* passes. The fork *m* has connected thereto a vertical rod *n* of such size as to slide through the vertical bearing *c*. Pinned to the lower end of the rod *n* by means of a 25 pin *p* is a block *q*. This block has provided at either side thereof grooves in which are mounted laminated knives *r* upon a pivot pin *s*.

30 *t* are flat springs adapted to press the knives *r* normally inward.

35 *s'* is a stop for limiting the inward movement of the knives. The lever *f* extends beyond the pivot pin *e* for a distance and has connected at the extremity one end of a long tension spring *u*, the other end of 40 which spring is suitably attached to the lower portion of the standard *b*.

45 *v* is a base plate of wood or other suitable material so located as to bring the neck of the bottle or table resting thereon at about 40 the correct height to be operated upon by the knives.

50 In order to enable the adjustment to be effected for bottles varying somewhat in size, I mount upon the table two circular blocks *w* by means of eccentrically placed screw pins *z* upon such table, so that by loosening the pins and turning the blocks to a similar extent to one another the desired 55 amount of adjustment is effected. For enabling the height of the table *v* to be adjusted I mount the same upon a flat spring strip *2* which is attached by means of a screw *3* to the base plate *a*; the height of which can be adjusted by regulating another screw *4*. Formed with the base plate *a* is an upwardly projecting portion *5* forming a rest for that portion of the neck of the bottle to be operated upon by the knives.

60 Attached to or formed with the rest *5* is a circular sleeve *6* the center of which comes at about the height of the center of the bottle. In the aperture on the said sleeve is mounted a rod or plug *y* of vulcanized fiber 65 or other suitable material. The amount by

which the said rod or plug projects from the sleeve *6* may be regulated and its position may be fixed by means of a screw *8*.

9 Figure 1 is a collar passing over the sleeve *6* and adapted to be held in any suitable position thereon by means of a set screw *10*. This sleeve carries a plate *11* provided at the outer end with two projecting pins *12*. By adjusting the collar *9* upon the sleeve *6* the position of the pins with respect to the end 75 of the neck of the bottle may be varied.

75 The method of using the machine will be readily understood: The required adjustments are first of all made with respect to the table *v* and other associated parts so that the bottles are laid in position upon the table with the necks coming upon or above the rest *5* and the end of the stopper or the like against the plug *y*; the capsule or the like to be stripped off comes vertically beneath the block *q* carrying the knives. The distance between the knives *r* is also correctly chosen according to the capsules to be removed, so that the edges of the knives come slightly closer together than the diameter of the capsule. The knives are now brought down by depressing the handle *g* against the pull of the spring *u* and the edges of the knives catching in the metal of the capsule, cut the metal and then the edges 85

90 moving farther down and riding over the neck of the bottle cause the knives to be separated against the action of the springs *t*, opening out the metal of the capsule, owing to the wedge shape of the ends of the 95 knives. These effectively loosen the capsule and leave it in a condition ready to be easily removed, or knocked off by means of the pins *12*.

100 After releasing the handle *g* so that the block *q* and the knives are raised 105 out of the way owing to the pull of the spring *u* the bottle is moved toward the right so that the loosened capsule comes against the pins *12* which knock off the 110 parts into a suitable receptacle placed beneath the machine.

110 In order to enable the capsules of different sizes to be removed by the same machine I may provide blocks *q* with knives at different distances apart, or I may so make the knives that the distances 115 between them can be adjusted by means of screw or other adjustments, which adjustment also effects the variation of the size of the stop. Owing to the cutting devices being formed of a number of laminæ the cutting devices can accommodate themselves to the conformation of the inequalities of the necks of the bottles or the like from which the capsules are to be removed.

120 Referring to the form of the device shown at Fig. 4, in this case 13 is a rubber block suitably mounted upon the base plate *a* of the machine. This rubber block is shaped to conform to the contour of the outside of the sleeve or capsule. *r* is a single knife, 125

which is preferably laminated, and which is adapted to be brought down by the action of the machine into contact with the capsule which it cuts and tears, the rotation of the sleeve or capsule upon the neck of the bottle being prevented by its contact with the rubber pad 13.

Fig. 5 shows another modification in which a rubber block 14 is provided furnished with 10 longitudinally extending ribs against which the sleeve or capsule is pressed to prevent its rotation upon the neck of the bottle while the knife or set of knives is operating.

Fig. 6 shows another modification in 15 which a ledge 15 is provided furnished with a chisel-shaped edge, a rubber block 16 being also provided and suitably shaped for the sleeve or capsule to rest within or against a recess therein while it is being operated 20 upon by the knife or set of knives *r*. In this case should any slight tendency exist for the sleeve or capsule to rotate upon the neck of the bottle in spite of its frictional contact with the block 16, the chisel edge of the 25 ledge 15 will be forced into the metal of the capsule and assists in cutting and tearing the same.

In the form of the device shown at Fig. 7 the sleeve or capsule rests upon two pivoted 30 chisel-edged knives 17, which knives are pressed normally upward by means of a spring 18. These knives prevent the rotation of the capsule or sleeve while it is being operated upon by the knife or set of knives 35 *r* or if any slight rotation should take place the knives 17 themselves contribute a certain amount of cutting and tearing action.

Fig. 8 shows a further modified form in 40 which the capsule rests at the bottom upon the base plate or equivalent part *a* and in which a pivoted knife 19 is provided attached to a vertical member 20, and pressed normally outward against the sleeve or capsule by means of a spring 21. This knife 19 45 contributes to prevent the sleeve or capsule rotating upon the neck of the bottle while being operated upon by the knife or set of knives *r* or in the event of rotation taking place helps to cut and strip the capsule from 50 the bottle.

It is to be understood that the method just described of constructing the apparatus is given merely by way of example, as the 55 details of construction may be varied largely to suit requirements of the article from which the capsule or the like is to be stripped and the class of capsule or other device to be removed.

Various means may be provided for 60 adapting the table to receive bottles or the like of different sizes and for bringing the capsules into the correct position to be operated upon by the knives. In place of operating the apparatus by means of a handle it 65 may be operated by means of a foot lever

or by other than manual power. Instead of causing the device carrying the knives to move up and down in order to operate upon the neck of the bottle in some cases the knives may be mounted in a stationary device and the bottle may be raised or brought against the knives for the same purpose.

What I claim and desire to secure by Letters Patent of the United States of America is:—

1. In a machine for removing capsules from bottle necks, the combination of means to prevent rotation of the capsule, means adapted to cut away said capsule and springs acting on said cutting means, adapted to 70 press said cutting means into said capsule.

2. In a machine for removing capsules, the combination of means to prevent rotation of the capsule, laminated cutting means adapted to conform to irregularities in said 75 capsule and springs acting on said cutting means adapted to press said cutting means into said capsule.

3. In a machine for removing capsules from bottle necks, the combination of means 80 for holding the capsule, laminated cutting members adapted to conform to irregularities in said capsule, said cutting members adapted to cut in opposed directions with respect to said capsule.

4. In a machine for removing capsules from bottle necks, the combination of a support for the bottle, and a pair of knives for engaging the bottle neck from opposite sides to cut away the capsule and prevent rotation 100 during the cutting operation, said knives comprising each a plurality of individually movable members arranged to follow irregularities in the capsule, substantially as described.

5. In a machine for removing capsules from bottle necks, the combination of a support for the bottle neck, a reciprocating head mounted above said support, means for actuating said head, a central stop in said 105 head, a pair of knives pivotally mounted in said head and arranged to engage the capsule at opposite sides to prevent rotation during the cutting operation, said knives comprising each a plurality of individually movable members adapted to follow irregularities in the capsule, and comb springs provided with teeth independently engaging each of the movable members of said knives and normally maintaining the same against 120 said stop, substantially as described.

6. In a machine for removing capsules, the combination of a support for the capsule, means for cutting away the capsule, and adjustable means for stripping the capsule after the same has been cut, substantially as described.

7. In a machine for removing capsules, the combination of a support for the capsule, means for cutting away the capsule,

an arm provided with a plurality of stripping pins, and means for adjusting said arm, substantially as described.

8. In a machine for removing capsules from bottles and the like, fixed means for supporting the bottle neck, an adjustable table for holding the bottles to position the necks upon said fixed support, and means for cutting away the capsule, substantially 10 as described.

9. In a machine for removing capsules from bottles and the like, the combination of a fixed support for the bottle necks, a table for holding the bottles, adjustable means 15 carried by said table for positioning bottles of varying size, and means for cutting away the capsule, substantially as described.

10. In a machine for removing capsules from bottles and the like, the combination 20 of a fixed support for the bottle necks, a table for supporting the bottles, means for adjusting the height of said table, means carried by said table for centering the bottles to properly position the necks thereof 25 on said support, and means for cutting away the capsules, substantially as described.

11. In a machine for removing capsules from bottles and the like, the combination 30 of a support for the bottle necks, a table for holding the bottles, means for adjusting said table to accommodate bottles of varying size, means for centering different sized bottles to properly position the necks thereof on 35 said support, means for cutting away the capsule, and means for stripping the cut capsules from the bottle necks, substantially as described.

12. In a machine for removing capsules from bottles and the like, the combination 40 of a support for the bottle necks, an adjustable table for holding the bottles, means for centering different sized bottles to properly position the necks thereof on said support, means for cutting the capsules, means for 45 stripping the cut capsules from the bottle necks, and means for adjusting said stripping means, substantially as described.

13. In a machine for removing capsules from bottle necks, the combination of a 50 frame, a support for the bottle neck mounted on said frame, an adjustable core associated

with said support for engaging the end of the bottle neck, and means mounted on said frame for cutting away the capsule, substantially as described.

55

14. In a machine for removing capsules from bottles, the combination of a frame, a support for the bottle neck mounted on said frame, a sleeve connected to said support, a core mounted for axial movement through 60 said sleeve, means for adjusting said core, and means for cutting away the capsule, substantially as described.

15. In a machine for removing capsules from bottles, the combination of a frame, a support for the bottle neck mounted on said frame, a sleeve connected to said support, an adjustable core mounted in said sleeve and adapted to engage the bottle neck, means for cutting away the capsule, and means for 70 subsequently stripping the capsule comprising an arm adjustably mounted on said sleeve, and pins on the outer end of said arm, substantially as described.

65

16. In a machine for removing capsules 75 from bottle necks, the combination of a frame, a support for the bottle neck rigidly mounted on said frame, a table for supporting the body of the bottle adjustably mounted from said frame to accommodate bottles 80 of varying size, a sleeve associated with said neck support, an adjustable core mounted in said sleeve for engaging the bottle neck, stripping means associated with said sleeve, a reciprocating head mounted in said frame, 85 means for actuating said head, a pair of oppositely disposed knives pivoted in said reciprocating head and adapted to engage the capsule at oppositely disposed points to prevent the rotation thereof during the cutting operation, each of said knives comprising a plurality of individually movable members, and individual springs for normally maintaining the members of each of 90 said knives in yielding contact with the capsule, substantially as described.
